UNITED STATES PATENT OFFICE.

ROBERT GOOD, OF WASHINGTON, PENNSYLVANIA, ASSIGNOR OF ONE-HALF TO HAZEL-
ATLAS GLASS COMPANY, OF WHEELING, WEST VIRGINIA, A CORPORATION OF
WEST VIRGINIA.

RECUPERATOR.

Application filed February 9, 1923. Serial No. 618,035.

To all whom it may concern:

Be it known that I, ROBERT Good, a citizen of the United States, and a resident of Washington, in the county of Washington and State of Pennsylvania, have invented new and useful Improvements in Recuperators, of which the following is a full, clear, and exact description.

One of the serious disadvantages of previously known recuperator constructions has been the leakage between the air flues and the waste gas passages; and one of the objects of the present invention is to provide a construction which will prevent such leakage.

Another object of the invention is to provide a recuperator which possesses a very high degree of durability, and in which the construction is such that the tiles, brick, etc., may be removed and renewed, when necessary, with comparative ease.

Other objects and advantages of the invention will be apparent to those skilled in the art from the following detailed description, when taken in connection with the accompanying drawings, in which:

Figure 1 is a longitudinal, vertical, sectional view of the recuperator.

Figure 2 is a vertical sectional view taken on line 2—2 of Figure 1; and

Figure 3 is a detail sectional view, on an enlarged scale, and clearly showing the relative arrangement of the tile and brick, and the joint therebetween.

Referring to the drawings more in detail, numeral 1 indicates the usual recuperator walls, having the ordinary air intake port 2 provided adjacent the bottom thereof. A plurality of I beams 3 are mounted in the recuperator walls above the air intake port, and on these I beams rest the base blocks 4. These base blocks support the tiles forming the air flues, as will appear hereinafter.

It will be understood, of course, that the base for supporting the tiles may be of any desired construction, and that the specific construction thereof, as illustrated and described herein, is merely the preferred form.

The recuperator includes a plurality of vertical flues for the passage of the combustion air to be preheated, said flues being indicated by the numeral 5; and a series of horizontal passages for the waste gases, said

horizontal passages being indicated by numeral 6.

The vertical flues are formed of a series of tiles, all of which are identical in construction. The tiles are indicated by numeral 7, and they are nothing more than conventional tiles having the usual bell mouth at one end, and being plain at the other end; so that the plain end of one tile fits into the bell mouth of the tile below it. The construction is obvious from an inspection of the drawings; the plain end of one tile is received within the flange 8 of the next lower tile, and the plain end rests on the shoulder 9 of this lower tile. The tile illustrated herein are formed with a single passage therethrough; but tiles having a plurality of passages are well known, and, of course, the present invention contemplates the use of such tiles, if preferred. The tiles are shown herein as rectangular in cross section, though any other form may be employed, if preferred. Further, the tiles forming the vertical flues are shown as having the bell mouth at the top, but it is obvious that the arrangement could be reversed, so that the bell mouth would be at the lower end of each tile; in which case the bell mouth of the lower end of a tile would fit over the upper plain end of the next lower tile.

The horizontal passages for the waste gases are formed by a plurality of horizontal baffles, causing the gases to follow a circuitous course, as in the ordinary recuperator constructions; but the present invention discloses a novel means for forming and supporting the baffles or diaphragms. The bricks forming these baffles are indicated by numeral 10, and they are designed to fit between the vertical flues and be supported by the flanges or shoulders 8 of the vertical tiles, as clearly shown in the drawings.

The simplicity of the construction is apparent from the foregoing description. The vertical flues are formed of a series of conventional bell mouth tiles, and the horizontal passages for the waste gases are formed of baffles or diaphragms constructed of plates, bricks, or the like, supported on the bell mouth flanges. It is thus seen that the bell mouths possess a dual function; for they not only form a joint between the sec-

tions of the vertical flues, but they also act as a support for the bricks forming the horizontal baffles or diaphragms.

It is highly desirable that mortar or similar jointing material be employed in the construction of the vertical flues and horizontal passages, and the use of jointing material is illustrated in Figure 3, being referred to by numeral 11. It will be obvious from an inspection of Figure 3 that the construction and relative arrangement of the parts are such that the jointing material may be easily and effectively applied.

It will be apparent that in a recuperator constructed in the above described manner there will be no possibility for any leakage to occur between the air and waste gas passages in the normal operation of the recuperator, and nothing short of the breaking of one of the tiles will cause the mixing of the air and waste gases.

The courses of the air and waste gases through the recuperator are clearly indicated in the drawings; the course of the air being indicated by single headed arrows, and the course of the waste gases being indicated by double headed arrows. The waste gases are shown as traveling back and forth through a single passage; but it will be understood, of course, that the arrangement may be varied so that the gases will travel in one direction through two or more flues,

and then return through a similar number of passages located below.

It is to be noted that the vertical flues 35 constitute a series of independent chimneys, each presenting a free and unobstructed passage for the air to be heated.

What I claim as new and desire to secure by Letters Patent is:

1. In a recuperator construction, a plurality of vertical flues arranged in horizontal alignment, a plurality of horizontal baffles forming passages for the waste gases through the recuperator, said vertical flues 45 formed of conventional bell-mouth tiles arranged end to end, each of said horizontal baffles arranged in a continuous line from side to side of the recuperator and supported on the bell-mouth flanges.

2. In a recuperator construction, a plurality of vertical flues arranged in horizontal alignment, said vertical flues formed of conventional bell-mouth tiles arranged end to end, the vertical flues arranged in abutting 55 relation to form a continuous wall, the walls thus formed being spaced to form passages, a plurality of horizontal baffles arranged in said passages, said horizontal baffles arranged in a continuous line from side to side 60 of the recuperator and supported on the bell-mouth flanges.

ROBERT GOOD.
